N. J., a corporation of New Jersey

Application December 28, 1939, Serial No. 311,325

16 Claims. (Cl. 274—1)

This invention relates to oscillation translating systems and more particularly to improved means for suppressing or mitigating undesired mechanical oscillations (i. e., vibrations) in such systems.

The invention has especial utility in combination with phonographic apparatus such, for example, as phonographic translating devices of the recorder type which convert acoustical or electrical oscillations into corresponding mechanical oscillations, and is herein described, without intending any unnecessary limitation thereto, in connection with such phonographic recorders.

It is to be noted that in cutting or impressing a progressive groove along the surface of a moving record by a phonographic recorder, the greater the depth of groove made by the recorder stylus, the greater is the force exerted by the moving record upon the stylus to move the latter out of the record. This action between the stylus and the moving record is like that of a compression spring—i. e., in the nature of a compliance—in that an increased penetration, or displacement, of the stylus into the record material is resisted by an increased restoring force. (It will be understood that the term "compliance" is herein employed in its usual sense to mean the deflection of a spring structure per unit applied force; however, inasmuch as there is no ordinary spring involved and the action of the recorder on a moving record is the equivalent of that of a spring, the character of this action will be hereinafter referred to as the effective compliance between the recorder and the record.) Such action is conducive to obtaining a constant depth of groove; in fact, by reason of this action the groove depth is commonly controlled by permitting a biasing of the recorder against the record to be taken up entirely by the force exerted upon the stylus by the moving record—i. e., by permitting the recorder to float by way of its stylus upon the surface of the moving record. When the groove depth is controlled in this manner there is, however, a strong tendency for a compliance usually principally made up of the effective compliance between the recorder and the record and otherwise of the compliance characterizing the recorder, to resonate with certain masses of the recorder (which masses may herein be referred to as the effective mass of the recorder). Such tendency towards recorder resonance renders the action of the recorder unstable. As a result, in the case of a vertical or hill-and-dale recording, the recorder becomes

highly sensitive to input oscillations at frequencies approaching the resonant frequency of the recorder, thereby rendering the frequency-response characteristic of the recorder non-linear; and in accentuated cases, the recorder is at times placed in sustained vibration in response to recurring shocks or external vibrations to cause a continuous modulation of the groove depth—which modulation results in the recordation of a constant note in a hill-and-dale type of recording and in tracking and other difficulties during the reproduction of a lateral type of recording. To suppress or mitigate these effects there has been employed a damped vibration absorber such as is described in my Patent No. 2,177,692, issued October 31, 1939, and entitled "Oscillation translating devices."

A damped vibration absorber as here mentioned is a particularly effective means for suppressing undesired vibrations in mechanical systems. A criterion for maximum effectiveness of the damped vibration absorber is, however, that it be tuned to a frequency bearing a definite relationship to the frequency of vibration to be damped or suppressed. This relationship is such that the absorber is tuned to a frequency slightly or appreciably below that of the vibration to be suppressed depending upon whether the effective (or damper) mass of the vibration absorber is small or large relative to the effective mass of the system to which the absorber is applied. Thus in the application of the vibration absorber to a phonographic recorder, the absorber will be effective to suppress a resonance effect between the recorder and the record only so long as there exists proper relative tuning between the absorber and the recorder.

It has been found that the resonant frequency of instability of a phonographic recorder does not remain constant but that it varies widely with temperature. This variation is caused by the effect of temperature on the effective compliance between the recorder and the record. This compliance may be considered equal to the product of a constant, depending principally upon peripheral record speed and shape of the recorder stylus, by a temperature-variable factor which depends for example upon such characteristics of the record material as its viscosity and stiffness. For record materials of wax-like character, such as is commonly used in records employed in connection with dictating machines, the viscosity and stiffness of the record material vary so as to cause an increasing effective compliance between the record and the recorder

with increasing temperature, and a decreasing effective compliance with decreasing temperature. In typical cases this effective compliance varies to cause the frequency of the recorder resonance to vary several times throughout an operating temperature range from 50° F. to 90° F., the variation being such that the recorder resonant frequency decreases with increasing temperature, and vice versa. In view of this variation, a damped vibration absorber whose natural (i. e., resonant) frequency either does not vary with temperature, or varies in widely different degree from that in which the resonant frequency of the recorder varies, will be incapable of suppressing the recorder resonance effects except within a limited ambient temperature range.

It is an object of my invention to provide means capable of suppressing or mitigating frequency-varying resonance effects in mechanical systems in highly efficient manner.

It is another object to effectively suppress, in mechanical systems, undesired vibrations which vary in frequency with temperature.

It is another object to provide a temperature-corrected form of damped vibration absorber.

Another object is to provide new and improved means in a vibration system by which there may be obtained a predetermined variation in the resonant frequency of the system with temperature change.

It is a further object of my invention to provide an improved phonograph system, and an improved phonographic recorder, wherein undesired vibrations are effectively mitigated or suppressed throughout wide temperature ranges.

It is a still further object of my invention to provide new and improved means and methods by which available damping materials may be employed to effectively suppress resonance effects having predetermined variations in frequency with temperature change.

Other and allied objects of my invention will more fully appear from the following description and the appended claims.

In the description of my invention reference is had to the accompanying drawings, of which:

Figure 1 is a partly elevational and partly vertical cross-sectional view of an acoustical recorder in which my invention is incorporated;

Figure 2 is a substantially horizontal cross-sectional view taken substantially along the line 2-2 of Figure 1;

Figure 3 is a cross-sectional view taken substantially along the line 3-3 of Figure 1;

Figure 4 is an enlarged sectional view taken along the line 4-4 of Figure 2;

Figure 5 is another sectional view taken substantially along the line 5-5 of Figure 4;

Figure 6 is a plan view, with parts in section, showing one particular form of my invention, as applied to the acoustical recorder of Figures 1 and 2;

Figure 7 is an elevational view of an electrical recorder in which my invention is incorporated;

Figure 8 is a plan view of the recorder of Figure 7 with a portion broken away, the support for the recorder being shown in cross section;

Figure 9 is a fractional view principally in section along the line 9-9 of Figure 8;

Figure 10 is a vertical cross-sectional view taken substantially along the line 10-10 of Figure 7;

Figure 11 is a vertical sectional view taken substantially along the line 11-11 of Figure 10; and

Figure 12 is an enlarged view in perspective of a portion of my invention as applied to the recorders of the prior figures.

My invention is illustrated herein, in Figures 1 through 6, in connection with an acoustical type of phonographic recorder (i. e., a recorder for directly converting acoustical oscillations into corresponding mechanical oscillation of a recorder stylus) and, in Figures 7 through 11, in connection with an electrical type of phonographic recorder (i. e., a recorder for converting electrical oscillations into corresponding mechanical oscillations of a recorder stylus). The application of my invention to the acoustical type of recorder may be first described.

Reference being had to Figures 1 and 2 there will be seen a typical form of acoustical recorder appearing as 1, and arranged for recordation upon a record R, which may for example be cylindrically shaped as shown. The recorder is carried by a carriage 2 which is mounted on a rod 3 for movement along the record R. During recording, the record R is rotated and the carriage 2 is concomitantly fed along the record as by a driving means not herein necessary to show.

The recorder 1 may comprise a frame 4 in the form of an inverted cup, which is provided with a central upwardly extending neck 5 and a front downwardly extending lug 6. Positioned below the frame 4 is a circular casing 7 which is pivoted to the lug 6 on a pin 8 for movement towards and away from the record. The bottom of the casing 7 is closed by a diaphragm 9 which carries a mounting 10 for a recorder stylus 10. This diaphragm and stylus are adapted to vibrate in accordance with input acoustical oscillations. Such oscillations are transmitted into the casing 7 by way of the neck 5 and a tube 11 which connects the neck to the casing, the tube being provided with upper and lower outwardly flanged portions 11' and 11'' of which the upper portion 11' slidably fits the neck 5 and the lower portion 11'' fits an apertured dome 11' on the casing, the lower portion being retained to the casing to form a universal joint therewith by a means not herein necessary to show. In this arrangement the casing 7 is free to move up and down relative to the record while yet being maintained in sound communication with the neck 5. A movement of the casing free of the record to place the recorder into inoperative condition may be effected, as desired, by means of an arm 12, partially shown, which may be moved into contact with a tab 13 on the casing to lift the recorder from the record.

It will be seen that in this structure the stylus 10 is biased against the record by the weight of the casing 7 and that this biasing force is counterbalanced by the force exerted upon the stylus by the record. During a recording operation, as when the record R is rotated and the carriage 2 is fed along the record, the stylus will form a progressive spiral groove in the record. This groove will be of a generally constant mean depth predetermined by the record and tool characteristics and by the biasing above mentioned; vibrations of the stylus 10 relative to the casing as because of acoustical oscillations being transmitted into the casing 7 will, however, cause the groove depth to be modulated in the case of a hill-and-dale type of recorder as is here shown. Since practical limitations may require that the weight of the casing 7 be more than is necessary to maintain a normal value of mean groove

depth, a portion of the weight of the casing may be relieved from the record by a counter-balancing structure 14. This structure is pivoted as at 15 to the underside of the frame 4 and is connected by a link 16 to the casing, the link being pivoted at 17 to the structure 14 and at 18 to the casing.

While acoustical oscillations conducted into the casing 7 will cause the diaphragm 9 and recorder stylus 10 to vibrate in response thereto the casing 7 will be largely prevented from movement in response to such vibration because of its own relatively large inertia. There is however, a tendency, as heretofore referred to, for the effective mass of the casing, as seen by the record, to resonate with a compliance made up of the effective compliance between the recorder stylus and the moving record and the compliance of the diaphragm 9. In this way there is formed with the effective mass of the recorder an undamped mechanical oscillatory system. As is well known, such systems are highly responsive to oscillatory influences approximating the frequency of resonance of the system. Indeed, in the present instance the influence on the casing 7 of the vibration of the recorder stylus at frequencies approximating the resonant frequency of the casing with the record may cause extremely large amplitudes of oscillation of the casing, which oscillations will cause similarly large amplitudes of oscillation of the recorder stylus 10. Thus frequencies of acoustical oscillations to be recorded which approximate the resonant frequency of the recorder will be translated into unduly large amplitudes of oscillation of the recorder stylus to cause the recorder to have a non-linear frequency response characteristic; and in accentuated cases, small yet unavoidable vibrations accompanying the operation of the phonograph may excite the recorder sufficiently to cause a sustained vibration of the casing 7 relative to the surface of the moving record at the recorder resonant frequency.

The damped vibration absorber of my aforementioned patent has proven itself an effective means for suppressing resonance effects in phonographic recorders, as above mentioned, provided there is no substantial variation in the conditions under which the phonograph is operated. It is found, however, as aforementioned, that because of the variation in characteristics of the record material with temperature the effective compliance between the recorder and the record increases and the resonant frequency of the recorder decreases with increasing temperature. Phonographs are normally operated within a limited temperature range of from 65° F. to 75° F.; yet frequently, as in the case of phonographs of the commercial or dictating machine variety, they are operated at temperatures below and beyond this limited temperature range, for example, as from 50° F. to more than 90° F. Within such a wide temperature range the recorder resonant frequency may vary by as much as two and one-half times—a variation in frequency far too great to permit effective suppression by means of the usual damped vibration absorber.

In accordance with the principle that the effectiveness of a damped vibration absorber is preserved so long as there is preserved a proper tuning of the absorber relative to the frequency of the resonance effects to be suppressed, I have found that there may occur variations both in the absolute frequency of tuning of the absorber

and in the frequency of the resonance effects to be suppressed, without loss in the effectiveness of the absorber, provided the variation in one approximates that of the other. In the instant invention I utilize this principle to effectively suppress the frequency-varying resonance effects in a recorder throughout a wide range of temperatures. This is done by causing the frequency of tuning of the damped vibration absorber to vary with temperature in substantially the same manner as that in which the resonant frequency of the recorder varies.

The damped vibration absorber comprises an anti-resonant structure which may be in various forms but which is preferably in the form of a resilient, cantilever-mounted beam structure 19 as shown for example in Figures 5 and 12. The beam structure 19 comprises a flat spring 20 having spaced channelled portions, a channelled inner or base portion 20a and a channelled outer or free-end portion 20b. Between and overlapping the channelled portions 20a and 20b there is applied a slab 21 of a damping material characterized by a high internal resistance as is hereinafter more fully explained; this slab is retained to the spring 20, as by suitable glue or by vulcanizing, and is secured at its end portions by means of ears 22 bent over from the channelled portions 20a and 20b into contact with the slab. The reason for a spring configuration having spaced channelled portions is that the length of the unchannelled or flat portion definitely establishes the effective length of bending of the beam structure and that the stiffness of this unchannelled portion will not be critical to clamping conditions at the channelled end portions of the structure.

At the free-end portion 20b of the spring 20 there is provided a localized weight 23 (see Figure 5) which is secured to the spring 20 by a screw 24, the screw passing through a slot 25 in the spring which extends longitudinally of the spring to permit an adjustment in the position of the weight relative to the spring, as for purposes of tuning the beam structure to a predetermined frequency. For the purpose of keeping the effective dynamic mass of the recorder low so that the recorder may present a not too high inertia reactance to the record, the beam structure 19 may well constitute a part of the counterbalancing structure 14 above mentioned. Accordingly the base portion 20a of the spring 20 is secured by a screw 26 to a mounting base 27 which in turn is secured as by welding to a cross bar 28 forming a part of the counterbalancing structure 14 as shown in Figure 2. This cross bar is secured by screws 29 to a U-shaped bracket 30 which is pivoted, as at 15, to a boss 31 extending down from the frame 4 of the recorder. Enclosing the beam structure from the atmosphere, to conserve the slab 21 of damping material, is a casing 32 which snugly fits the mounting base 27 and which is retained thereto as by a screw 33. In the arrangement here described it is seen that the vibration absorber (which includes the beam structure 19 and weight 23) and the casing 32 and supporting means for the absorber (which supporting means includes the mounting base 27, the cross bar 28 and bracket 30) are all included within the counterbalancing structure 14 of the recorder.

In the present instance there are employed two of the damped vibration absorbers, which absorbers have their analogous portions represented by identical reference characters. These ab-

sorbers are each included within the counterbalancing structure 14 and are respectively disposed on opposite sides of the sound tube 11. While I herein show two of the damped vibration absorbers it will be understood that my invention is not necessarily limited in respect of the number of vibration absorbers employed.

The preferred arrangement of damped vibration absorber is one having a temperature-resonant frequency characteristic which is substantially similar to the temperature-resonant frequency characteristic of the recorder throughout the operating range of temperatures, this range typically being from 50° F. to 90° F. as aforementioned. With such arrangement there will be preserved at each discrete temperature within this range a substantially fixed ratio of tuning between the damped vibration absorber and the resonant frequency of the recorder, thereby maintaining the damped vibration absorber at its optimum efficiency. Such a temperature-resonant frequency characteristic of the vibration absorber will be realized provided the compliance of the beam structure 19 varies with temperature in substantially the same way as that in which the effective compliance between the recorder and the moving record varies.

I have found that there is available a material which has a compliance that varies with temperature in substantially the manner just noted throughout the temperature range from 50° F. to 90° F., and that this material has, moreover, a considerable internal resistance. This material is a synthetic rubber known by the trade name of "Neoprene." In adapting a slab of this damping material to the beam structure above described I make the spring 20 relatively thin so that it will contribute little to the stiffness of the structure, thereby permitting the slab of "Neoprene" to be the controlling factor in the determination of the temperature-compliance characteristic of the beam structure. Even though the spring 20 is made relatively thin, it yet has several very desirable actions: First, it prevents cold flow (i. e., permanent deformation) in the slab of damping material, and second, because of its channelled end portions, it definitely determines the active length of the slab of damping material and provides ready means by which the damping material may be supported at one end and suitably loaded at the other without critical effect upon the compliance of the beam structure.

While "Neoprene" has the very desirable temperature-compliance characteristic above mentioned, the damping capabilities of a single absorber employing "Neoprene" may in certain applications be found to be insufficient. Should this occur, the effectiveness of the absorber may, however, be increased by increasing the width of the beam structure 19. Such increase in width will increase the stiffness and the effective mass of the beam structure. This increase in stiffness and mass of the beam structure will, however, be in the same degree and be without effect upon the tuning of the beam structure unless the effective mass of the beam is increased by a localized weight, such as 23, in which case the weight will also have to be increased to maintain the proper relative tuning. A widening of the beam structure may also be accomplished, in effect, by the use of a plurality of similar beam structures. In the present case I have resorted to the latter expedient, there being employed two identical beam structures each having a

temperature-resonant frequency characteristic substantially conforming to that of the recorder throughout the operating temperature range from 50° F. to 90° F. It is found that these two structures, or damped vibration absorbers, effectively suppress the resonance effects in the recorder throughout the temperature range here noted.

A commercially available damping material having considerably better damping capabilities than "Neoprene" is a cellulose nitrate plastic known by the trade name of Du Pont "Viscoloid." While this damping material has the advantage of high internal resistance it has the disadvantage, in the present application, that its compliance varies with temperature at a rate much faster than that of the effective compliance characterizing the action between the recorder and the moving record. If a beam structure were, for example, made up by applying a slab of this damping material to a relatively thin spring (as in the manner above described in connection with "Neoprene") to form a structure wherein the damping material constitutes the principal stiffness-controlling element, this structure would have very good damping capabilities; but it would have a fast rate of change in its resonant frequency with temperature because of the steep temperature-compliance characteristic of the "Viscoloid," and could therefore remain in proper relative tuning to the recorder only within a narrow temperature range. At temperatures out of this range the effectiveness of the absorber would be very materially reduced. To cover the temperature range of from 50° F. to 90° F., there would then need to be employed a large number of such vibration absorbers, which absorbers would be successively tuned at predetermined frequency intervals, the intervals being substantially twice the permissible variance in relative tuning between one of the absorbers and the recorder while yet preserving the effectiveness of that absorber.

Thus it is seen that while a beam structure formed principally of "Viscoloid" has high damping capabilities, it is not particularly well suited as a vibration absorber for the suppression of the effects arising from the temperature-varying resonant frequency of the recorder, because such a beam structure has a resonant frequency which varies with temperature at a rate much faster than that in which the resonant frequency of the recorder varies. I have found, however, that damping materials generally, particularly those having high damping capabilities and high ratio of change in compliance with temperature, such as is characteristic of "Viscoloid," may be employed in a manner to produce beam structures having any preassigned lower rates of change in their temperature-resonant frequency characteristics; and moreover that these beam structures will yet exhibit the damping capabilities of the damping material itself to considerable degree, depending upon the difference between the temperature-resonant frequency characteristic of the beam structure so produced from that of the damping material itself. In view of the significance of proper relative tuning between a vibration absorber and the system to which it is applied, I may in accordance with my invention form a beam structure for a vibration absorber having a rate of change in its resonant frequency with temperature predetermined to conform to the temperature-resonant frequency characteristic of the system to which the absorber is applied,

and thereby preserve the effectiveness of the absorber through increased ranges of temperature. The formation of this beam structure is now explained.

Since metals have a compliance essentially unresponsive to temperature, within the range of present interest, it is found that beam structures comprising a combination of metal and damping material (for example, one of the general form hereinabove described) may be designed to have temperature-compliance characteristics predetermined within the range between that of the metal itself and that of the damping material itself, depending upon the proportioning of metal to damping material. As the ratio of metal to damping material is increased the damping capabilities of the beam structure so formed will be reduced. However, when a material of high damping capabilities such as "Viscoloid" is used in the beam structure, I find that by a proper proportioning of metal to damping material the temperature-resonant frequency characteristic of the beam structure can be made to conform closely to that of the recorder through a wide range of temperature while yet retaining in the beam structure sufficient damping capabilities to preserve the effectiveness of the absorber throughout such temperature range. Thus by the expedient of combining metal and "Viscoloid" or other commercially available materials of high damping capabilities, I may form a beam structure for a vibration absorber which will effectively suppress a temperature sensitive frequency-varying resonance through a temperature range considerably increased over that in which a beam structure made principally of such damping material will be effective.

In utilizing combined metal-viscoloid beam structures of the type just described I find that a single vibration absorber employing such structures will effectively suppress the recorder resonance through substantially half of the entire operating temperature range of from 50° F. to 90° F., and that two such vibration absorbers when properly relatively tuned will by their combined action cover easily the entire operating temperature range. To effect such proper relative tuning the absorbers are respectively tuned, at a mean ambient temperature of say 70° F., above and below the frequency of resonance of the recorder at this temperature, the tuning being done for example by adjusting the weight 23 along the spring 20 into relative positions such as is indicated in Figure 6. The mistuning of the absorbers relative to the recorder is, however, restricted so that the combined or straddling action of the two absorbers will just effectively suppress the resonance effects of the recorder throughout the region of the mean temperature. In the temperature range below the mean temperature above noted, the resonant frequency of one of the absorbers will with temperature change approach, become equal, and then go beyond the resonant frequency of the recorder; and, in the temperature range above the mean temperature there will occur a similar relationship between the resonant frequency of the other absorber and that of the recorder. Thus, throughout the entire temperature range either one or the other of the absorbers will be sufficiently closely tuned in relation to the recorder to effectively suppress the recorder resonance or else, as in the region of the mean temperature, the two will be respectively sufficiently closely tuned to the recorder so that their

combined action will result in an effective suppression of the recorder resonance.

It will be seen that in the arrangement just described I have employed a commercially available damping material in a vibration absorber in a manner to obtain a wide temperature coverage with a limited number of such absorbers. This was accomplished by employing a plurality or multiplicity of predeterminedly differently tuned beam structures wherein the ratio of metal to damping material is substantially the maximum permissible while yet retaining in the beam structures effective damping action. While I obtain particularly beneficial results by a multiple arrangement of carefully relatively tuned beam structures of the type just described, it will be understood that in accordance with this multiple-absorber aspect of my invention, I am not necessarily limited with respect to the type of individual beam structure employed. I may, for example, employ lower ratios of metal to damping material, or even beam structures comprising principally the damping material alone, and yet obtain efficient suppression over a very material temperature range by employing multiple arrangements of such beam structures as when the structures are carefully differently tuned. Moreover, it will be understood that in accordance with the principles herein disclosed in regard to multiple arrangements of vibration absorbers, my invention does not necessarily contemplate an absolute change in the frequency of the resonance to be suppressed but rather a relative change with temperature between such resonant frequency and the natural frequency of the respective vibration absorbers; and that on the basis of this principle I may employ, in absorbers, damping materials having steep temperature-compliance characteristics and yet suppress through wide temperature ranges an essentially constant-frequency resonance by means of a limited number of such absorbers respectively differently tuned at predetermined frequency intervals.

In Figures 7 through 11 there is shown the application of the damped vibration absorber of my invention to an electrical phonographic recorder. Such a recorder may comprise an oblong frame 35 having a converging end portion 35' (see Figure 8) and a flange 36 extending downwardly along its sides to form a shell-like structure. In the converging end portion 35' of the frame there is provided the recorder proper which, by way of example, is shown in the form of a triangularly-shaped piezo-electric bending unit 37 of the so-called "bi-morph" type—e. g., comprising two thin crystals secured face-to-face and arranged for simultaneous voltage application thereto by way of leads 38 to cause one crystal to expand longitudinally as the other contracts, and vice versa, whereby to result in a bending of the unit. The bending unit 37 is cantilever-mounted between two similar trapezoidally-shaped plates 41 which have base portions 41' of increased thickness bearing against the base portion of the bending unit; the remaining portion of the unit is left free for vibration in accordance with electrical oscillations impressed on the leads 38 and on the free end of this portion there is provided a holder 39 carrying a recorder stylus 40. The assembly of the plates 41 and bending unit 37 is secured to the underside of the end portion 35' of the frame by four screws 42 which are located beyond the bending unit at the corners of the plates 41. Each of these screws pass freely through the

top of the frame 35 and through the upper one of the plates 41. The two screws which are at the free end of the unit however thread into the lower one of the plates 41 while the other two screws, the ones in the base portion of the plates 41, pass freely through the lower one of the plates and then thread into a metal strip 43, whereby to clamp the assembly of the plates and bending unit against the top of the frame 35.

The strip 43 is provided with turned-back end portions 44 which extend along the inner sides of the side flanges 36 and terminate into inwardly extending bosses 45. Threaded through the bosses 45, by way of openings 46 in the side flanges 36, are pivot screws 47 having conical end portions which engage respectively with a pair of spaced arms 48. These arms extend upwardly through an opening 49 in the top of the frame 35 and thereafter converge into a shank 50 of a support for the recorder.

For the purpose of suppressing or mitigating resonance effects of the bending unit itself, and for safeguarding the unit from excessive strain such as may be occasioned by improper handling of the recorder, there is provided a pair of resilient pads 51, made for example of rubber, which are interposed at the free end of the bending unit between the unit and the upper and lower plates respectively.

This electrical recorder, the same as the acoustical recorder hereinbefore described, is biased by its own weight to maintain a normal coaction between the recorder stylus and a record R which may, for example, be of cylindrical shape. During recording the record R is rotated and the recorder is progressively moved therealong as by a suitable driving means, which driving means is however not herein necessary to show. Movement of the recorder from the record, for example to permit a change of record, may be effected by a lifting arm 52, partially shown, which may be raised to contact a tab 53 on the frame to thereby raise the recorder proper from the record.

In the electrical recorder above described there may occur a resonance between (a) a compliance made up of the effective compliance arising from the coaction between the recorder stylus 40 and the moving record and the compliance of the bending unit 37, and (b) the effective mass, as seen by the record, of the entire recorder. In the frequency region of this resonance the recorder may become inordinately highly sensitive as in the manner heretofore described in connection with the acoustical type of recorder; and, as in the case of the acoustical recorder, the frequency of this resonance will vary with temperature because of the temperature-varying characteristics of the record material. To suppress effects of such resonance I may employ damped vibration absorbers which may be in their construction in all respects similar to either of the two types of vibration absorbers above described in connection with the acoustical recorder—i. e., the respective types described in connection with the damping materials, "Neoprene" and "Viscoloid."

The beam structures 18 of the damped vibration absorbers are preferably directly coupled to the frame 35 and mounted in counterbalancing arrangement relative to the recorder proper. The preferred mounting arrangement for these vibration absorbers is one in which the beam structures of the absorbers are mounted transversely of the frame 35 with their base ends re-

spectively at opposite sides of the frame. The absorbers may be mounted in this manner, and may be moreover enclosed from the atmosphere so as to conserve the damping material employed in the absorbers, by a mounting means in the form of a cylindrical container 54 which in length is adapted to fit between the side flanges 36 of the frame 35.

The container 54 comprises a tube 55 having counterbored ends into which are fitted relatively thick end walls 56. The container is held on the frame 35 by means of screws 57 which pass through the side flanges 36 and thread into the end walls. The end walls 56 are similarly shaped and respectively provided on their inner sides with recesses 58 forming bases offset from the center of the end walls on which the vibration absorbers are respectively clamped as by the screws 59; the end walls are, however, oriented 180° from each other about the longitudinal axis of the container, so that the vibration absorbers will clear one another and have their movements commonly directed, and both end walls are oriented relative to the frame 35 so that the direction of movement of the absorbers will be substantially tangential relative to the path of the pivotal movement of the frame 35 on its supporting arms.

Although I have shown and described my invention in terms of several specific embodiments it will be understood that these embodiments are merely illustrative and not limitative of my invention, and that these embodiments are subject to many changes and modifications without departing from the scope of my invention, which I now undertake to express according to the following claims.

I claim:

1. In an oscillation translating system having a vibratable member, and means associated with said member and having a temperature-varying characteristic tending to produce with said member a frequency-varying resonance; a damped vibration absorber applied to said member to cause said resonance to be suppressed throughout a predetermined temperature range, comprising a resilient beam structure including two distinct resilient portions respectively having compliances varying with temperature at relatively low and high rates, said portions being associated with one another and having a predetermined proportional relationship to cause their combined compliance to vary with temperature in a degree substantially maintaining the same relative tuning between said beam structure and the frequency of said resonance throughout said temperature range.

2. In an oscillation translating system having a vibratable member characterized by a resonant tendency varying in frequency with temperature: a damped vibration absorber operatively associated with said vibratable member and comprising a plurality of distinct resilient portions respectively having compliances varying with temperature at different rates, and the combined compliance of said portions varying with temperature throughout a substantial temperature range in a degree to maintain throughout said temperature range a substantially fixed ratio of tuning between the natural frequency of said absorber and the frequency of said resonance.

3. In an oscillation translating system having a vibratable member characterized by a resonance varying in frequency with changes in the ambient temperature: a damped vibration absorber for

causing said resonance to be suppressed throughout a predetermined temperature range, comprising a multi-layer beam structure having a layer of material of high resilience relatively insensitive to temperature and another layer of material of low resilience highly sensitive to temperature, and the dimensions of said layers being proportioned to maintain throughout said temperature range a substantially fixed ratio of tuning between the natural frequency of said beam structure and the frequency of said resonance.

4. In an oscillation translating system having a vibratable member characterized by a resonant tendency varying in frequency with temperature: a damped mechanical oscillating structure applied to said member to cause said resonance to be suppressed throughout a predetermined temperature range, comprising a bi-layer resilient beam and a localized mass mounted thereon, one layer of said beam consisting of a material having a resilience substantially insensitive to temperature and the other layer of said beam consisting of a material having a high internal resistance and a resilience relatively highly sensitive to temperature, and the relative dimensions of said layers being proportioned to maintain throughout said temperature range a substantially fixed ratio of tuning between the natural frequency of said beam and the frequency of said resonance.

5. In an oscillation translating system: the combination of a vibratable member; and means effective to suppress vibration of said member, comprising a plurality of damped vibration absorbers each applied to said member and each including a resilient structure having a compliance varying with temperature and causing the natural frequency of the absorber to vary with temperature in relation to the frequency of said vibration, said absorbers being characterized by optimum effectiveness when their frequencies bear a predetermined ratio to the frequency of said vibration, and the tuning of said absorbers being at frequency intervals whereby to cause at least one of the natural frequencies of said absorbers to bear at least approximately said predetermined ratio to the frequency of said vibration at any temperature within a substantial temperature range.

6. In an oscillation translating system: the combination of a vibratable member in said system; and means for suppressing vibration of said member, comprising a plurality of tuned damped vibration absorbers each effective on said member and each having a resilient portion characterized by a compliance varying with temperature and causing the natural frequencies of the absorbers to vary in relation to the frequency of vibration of said member, and the tuning of said absorbers being at predetermined frequency intervals.

7. In an oscillation translating system: the combination of a vibratable member; means associated with said member and having a temperature-varying characteristic tending to produce a frequency-varying resonance with said member; and means to suppress said resonance comprising a plurality of damped vibration absorbers effective on said member and each including a resilient beam structure having a compliance varying with temperature and causing the natural frequency of the beam structure to vary with temperature in relation to the frequency of said resonance, said beam structures being successively tuned to the frequencies attained by said resonance at predetermined temperature intervals progressively spaced.

8. In an oscillation translating system having a vibratable member characterized by a resonance varying in frequency with temperature: means for causing said resonance to be suppressed throughout a predetermined temperature range comprising a plurality of damped vibration absorbers each applied to said vibratable member and each having a natural frequency varying in frequency with temperature in the same direction but to a different degree from that in which the frequency of said resonance varies, said absorbers being characterized by optimum effectiveness when their natural frequencies bear a predetermined ratio to the frequency of said vibration, and the tuning of said absorbers being at frequency intervals whereby to cause at least one of the natural frequencies of said absorbers to bear at least approximately such ratio to the frequency of said resonance at any temperature within said range.

9. In an oscillation translating system having a vibratable member and means associated with said member and having a temperature-varying characteristic causing a frequency-varying resonance with said member: the combination of means for suppressing said resonance throughout a predetermined temperature range, comprising a plurality of predeterminedly differently tuned damped vibration absorbers each effective on said member and each actively including a resilient beam structure comprising a slab of damping material having a compliance varying with temperature and causing the natural frequency of the slab to vary at a substantially faster rate than that in which the frequency of said resonance varies, and means applied to said respective slabs and opposing the variation in compliance of said slabs whereby to cause the difference between the rate of variation in the natural frequency of each beam structure and of said resonant frequency to be substantially less than the difference between the rate of variation in the natural frequency of each slab of damping material and said resonant frequency.

10. In a phonographic translating device: the combination of a movably mounted holder; a vibratile means supported by said holder for coaction with a moving record, said coaction tending to cause a resonance between the holder and the moving record the frequency of which varies with temperature of the record; and a tuned damped vibration absorber coupled to said holder and effective as to vibrations of said holder relative to the record, said vibration absorber having a resilient beam structure comprising a damping material having a compliance varying with temperature throughout a predetermined range and causing the natural frequency of the damping material to vary at a substantially faster rate than that in which the frequency of said resonance varies, and a resilient material having a compliance substantially unresponsive to temperature and applied to said damping material in a proportion to maintain a substantially fixed ratio of tuning between the natural frequency of said beam structure and the frequency of said resonance throughout said temperature range.

11. In a phonographic translating device: the combination of a movably mounted holder; a vibratile means supported by said holder for coaction with a moving record, said coaction tending to cause a resonance between the holder and the moving record the frequency of which varies with temperature of the record; and a damped vibration absorber for suppressing vibration of said

holder within a predetermined temperature range, comprising a resilient beam structure having two distinct portions, said portions respectively having compliances varying with temperature at relatively low and high rates, and said portions being combined in predetermined proportional relationship to cause said absorber to have a frequency-varying resonance approximating throughout a substantial portion of said temperature range the frequency of resonance between said holder and moving record.

12. In a phonographic translating device: the combination of a movably mounted holder; a vibratile means supported by said holder for coaction with a moving record, said coaction tending to cause a resonance between the holder and the moving record the frequency of which varies with temperature of the record; and means for causing vibration of said holder to be effectively suppressed at all temperatures within a predetermined temperature range, comprising a plurality of damped vibration absorbers each including a damped beam structure having a compliance varying with temperature and causing its natural frequency to vary at a rate different from that in which the frequency of said resonance varies, said beam structures being respectively tuned to the frequencies attained by said resonance at predetermined temperature intervals progressively spaced within said temperature range.

13. In a phonographic translating device: the combination of a movably mounted holder; a vibratile means supported by said holder and coacting with the surface of a moving record, said coaction tending to cause a resonance between said holder and record the frequency of which varies with the temperature of the record; and means for causing said resonance to be suppressed throughout a predetermined temperature range, comprising a plurality of predeterminedly differently tuned damped vibration absorbers each coupled to said holder and each actively including a resilient beam structure comprising a damping material having a compliance varying with temperature and causing the natural frequency of the damping material to vary at a rate

substantially different from that in which the frequency of said resonance varies, and means in said respective beam structures applied to the damping materials thereof for causing the difference between the rates of variation of the natural frequencies of said beam structures and of said resonant frequency to be substantially less than the difference between the rates of variation of the natural frequency of said damping material and said resonant frequency.

14. In an oscillation translating system: a vibratable element forming a portion of said system and subjected to a vibratory influence; and damping means effective on said element to suppress vibration thereof, comprising a spring having a distinctly defined resilient portion interposed between relatively stiff inner-end and outer-end portions, said inner-end portion being secured to said element, a localized mass mounted on said outer-end portion, and a damping material retained in contact with said spring along said resilient portion.

15. In an oscillation translating system: a vibratable element forming a portion of said system and subjected to a vibratory influence; and damping means effective on said element to suppress vibration thereof, comprising a beam secured to and extending from said element and having spaced channel-shaped portions along its length; and a slab of damping material applied to said beam along the portion thereof between said channel-shaped portions.

16. In an oscillation translating system: a vibratable element forming a portion of said system and subjected to a vibratory influence; and damping means effective on said element to suppress vibration thereof, comprising a beam secured to and extending from said element and having spaced channel-shaped portions along its length; damping material applied to said beam along the portion thereof between said channel-shaped portions; and means on said channel-shaped portions bearing against said damping material to retain the same in contact with said beam.
